UNITED STATES PATENT OFFICE.

ROY BURCHILL, OF MITCHELL, ONTARIO, CANADA.

COMBINED EXCAVATOR AND LOADER.

Application filed July 8, 1928. Serial No. 291,272.

- The invention relates to improvements in combined excavators and loaders as described in the present specification and shown in the accompanying drawings which 5 form part of the same and has for its object the production of a serviceable and efficient easily operated excavator and loader which operates simultaneously with its propulsion over the ground being excavated.
- 10 According to the present invention, converging spiral screws are driven by traction power as the apparatus is advanced over the ground, which screws in their working position worm surface soil to their meeting point, where it is taken by a bucket wheel and fed to an inclined conveyor. The elevated soil is then received by a discharge conveyor which drops it into a wagon or truck for subsequent transportation.
- 15 Referring to the drawings, Figure 1 is a side elevation of the excavator and loader depicting a portion of the inclined conveyor in section to display the screw therein.
- 20 Figure 2 is a front view thereof showing more particularly the fore-carriage and the running gear.
- 25 Figure 3 is a similar view to Figure 2, omitting the fore-carriage and showing the running gear partly in section. This view 30 exhibits the spiral screws, bucket and the major part of the inclined conveyor.
- 35 Figure 4 is a plan view chiefly in section, of the driving gear for taking off power from the traction wheels.
- 40 Figure 5 depicts a part of one of the spiral screws and a vertical section of the driving gear therefor.
- 45 Figure 6 is a plan view of the running gear, spiral screws and bucket.
- 50 Figure 7 is a side elevation, mostly in section, of the top of the inclined conveyor and the associated portion of the discharge conveyor, illustrating the swivel connection therebetween.
- 55 Figure 8 is a side view of the bucket wheel.
- Figure 9 is a front view thereof.
- Figure 10 is a section taken on the line 10—10 of Figure 9 showing the shape of the buckets.
- 60 Like numerals of reference indicate corresponding parts in each of the figures throughout the drawings.
- In the drawings, the reference numeral 15 denotes the traction wheels which are of 65 substantial diameter and have driving connection with the live axle 16 extending
- through them; the wheels and axle form a part of the running gear or power take-off. The axle is mounted in a housing 17 by means of suitable bearings. Spaced at the rear of the axle 16 is a shaft 18 extending parallel therewith and rotatably supported in a housing 19 that is secured to the axle housing 17 as at 20. Both of the housings are enlarged as at 21 to one side of their longitudinal centres to provide a gear case 22. The case contains a pair of meshing gears 23 and 24 for driving the shaft 18 at a greater speed than the axle 16.
- The gear 23 is not directly connected to the axle 16 but operates through an ordinary clutch 25 that is manually controlled by the lever 26. Fastened to the gear 23 is a bevel gear 27 that meshes with a pinion 28 from which the shaft 29 rearwardly inclines in order to take off power for operating the inclined conveyor as hereinafter more fully described. This inclined shaft 29 may be supported by the bracket 30 or otherwise.
- The forecarriage 31 has the usual draw-bar connection 32 at its swivel and is connected to the running gear aforesaid by members 33.
- Rising from the forecarriage is a stationary screw 34 which loosely fits into a bracket 35 and has screw threaded engagement with a hand wheel 36 flanked on both sides by the said bracket so that upon the hand wheel being screwed up or down on the screw the bracket will be carried with it. Tie-rods 37 serve to connect the bracket to the ends of the axle housing 17 while uprights 38 rigidly secure it to the top end of the inclined conveyor tube 39. The lower ends of these uprights are rearwardly prolonged as 40 to attach to the lower end of the conveyor tube. By this construction, as the handwheel is turned in a direction to lower the bracket 35 it tilts the inclined conveyor raising its lower end. The axle 16 serves as the fulcrum point.
- The rearwardly converging spiral screws 41, 41, best discernible in Fig. 6, are journaled in the frame 42, the frontal part of which depends from the ends of the shaft 18 housing 19 so as to form separate hollow hangers 43 for supporting the divergent front ends of the spiral screws.
- A vertical stub shaft 44 is journaled in each hanger and connected to the shaft 18 by means of meshing bevel gears 45. The lower end of each stub shaft is connected

to the corresponding spiral screw by incased meshing gears 46 of a similar type, as best seen in Figure 5. Each hanger carries an inwardly inclined scraper 43'.

5 The rear of the frame 42 embraces the lower end of the tube 39 of the inclined conveyor and carries the rear ends of the spiral screws 41. These screws when in working position partly enter the ground 10 so that upon being turned they will worm soil rearwardly to their meeting point or vertex, the soil being accumulated between the screws.

The inclined conveyor comprises in addition to the tube 39 a conveyor screw 47 which extends from end to end thereof, its integral shaft 48 protruding from opposite ends of the tube. The protruding top end of this shaft is keyed to a spur gear 49 15 that meshes with a similar gear 50 likewise made fast to the shaft 51 running parallel to the tube and journalled in brackets supported thereby. The lower end of the shaft 51 is geared at 52 to the inclined 20 shaft 29 previously recounted. In this manner a driving connection is provided for the conveyor screw 47 so as to rotate it simultaneously with the spiral screws 41.

The lower end of the conveyor screw shaft 30 48 is supported by the bearing 53 integral with the arched bracket 54. The bucket wheel 55 is loosely mounted on this shaft so as to turn independently thereof. It is, however, driven by the shaft indirectly 35 through reduction gearing 56 preferably but not essentially of the bevel gear type illustrated in Figure 1.

The bucket wheel consists of an angle rim 57 the lower part of which has line contact 40 with the ground. The rim is integral with or secured to a back 58 and within the rim is a number of buckets 59 spaced equidistantly. Each bucket is composed of a front 60 and bottom 61. The bucket fronts 60 lie 45 in a plane at right angles to the axis of rotation of the wheel, while the bottoms are curved and extend radially inwardly from the rim to a point short of the centre or axis, thus forming scoops which scoop up the 50 soil gathered by the spiral screws 41 and as the bucket wheel rotates and the individual buckets approach the highest point thereof the contents gravitate to the centre of the wheel, where the conveyor screw 47 functions to impel the soil up the tube 39 to the 55 top thereof. The conveyor screw may extend slightly into the bucket wheel.

Advertising to the inclined conveyor, the tube 39 thereof has its top end closed and 60 joined to an integral downwardly turned elbow 62 that is swivelled at 63 in order that the lower part may swing in a horizontal plane. This lower part is rigidly affixed to the horizontal discharge conveyor 65 tube 64 whereby the contents fed to the top

of the inclined conveyor pass into the elbow 62 and from there into this discharge conveyor tube 64. The contents are wormed along this tube by the screw 65. Power is taken off of the inclined conveyor screw 47 for 70 this purpose by means of a shaft 66 geared at its frontal end as at 67 to the discharge conveyor screw 65 and connected at its rear end by bevel gears 68 to the shaft 48. The intermediate gear 65 has a vertical spindle 75 70 journalled in the elbow 62. A tie rod 71 supports the overhanging end of the tube 64.

71' is a discharge spout and 72 is an intermediate discharge spout controlled by a conventional gate 73. The latter is used only 80 when it is desired to discharge excavated soil in a shorter radius.

The discharge conveyor is manually swingable sidewise by means of a hand crank 74 connected to a drum 75 over which 85 a cable 76 is wound. The cable passes over guide pulleys 77 to a sheave 78 that is rigidly affixed to the bottom of the tube 64 coaxially with the swivel 62.

In the use of this invention, the device 90 is hauled from place to place with its rear end raised off the ground. In operation the rear end is lowered by turning the hand wheel 36 which brings the spiral screws 41 and bucket wheel 55 into working contact 95 with the ground. As the device is drawn over the ground these spiral screws worm the soil to the bucket wheel 55, the buckets of which feed it to the inclined conveyor screw 47. The elevated soil is precipitated 100 through the elbow 62 into the discharge conveyor and therein wormed to the spouts 71 and 72 for discharge into a truck or the like.

What I claim is:—

1. In an excavator and loader, driven spiral screws horizontally disposed for excavating soil, a rotatable bucket wheel cooperating therewith for receiving the soil, and an inclined conveyor of the incased screw type having its receiving end associated with said bucket wheel. 105

2. In an excavator and loader, power driven spiral screws horizontally disposed for excavating soil, said screws being convergently positioned and adapted to worm the soil to their converging ends, a rotatable bucket wheel positioned thereat, and an inclined conveyor having its receiving end associated with the bucket wheel. 115

3. In an excavator and loader, driven spiral screws horizontally disposed for excavating soil, a rotatable bucket wheel cooperating therewith for receiving the soil, an inclined conveyor of the incased-screw type having its receiving end associated with the bucket wheel, and scrapers positioned in advance of the spiral screws and inwardly inclined for diverting soil therebetween. 125

4. In an excavator and loader, driven 130

spiral screws, gearing for taking off power from said running gear in order to operate the aforesaid working parts, a forecarriage connected to the running gear, a screw rising 5 therefrom and held against rotation, a hand wheel having threaded engagement with the screw, a bracket loosely mounted upon the screw and flanking the hand wheel, and members rigidly connecting the bracket to 10 the said running gear.

13. An excavator and loader comprising an axle housing, an axle journalled therein, traction wheels fitted on the axle, a driving connection between the axle and one of the 15 wheels, a housing extending parallel to the aforesaid housing, a shaft rotatable therein, an enlargement extending from one to the other of the housings and constituting a gear casing, meshing gears therein and keyed to the axle and shaft, a frame secured to the housings, converging horizontally disposed spiral screws journalled in 20 said frame, gearing forming a driving connection between the aforesaid shaft and

spiral screws, an inclined conveyor of the 25 screw incased type supported by the frame and housings, a bucket wheel mounted on the bottom end of the inclined conveyor screw and to the rear of the spiral screws, and mechanism for taking off power from 30 the live axle to operate the inclined conveyor screw and bucket wheel.

14. In an excavator and loader, the combination with spiral screws for rearwardly worming soil and an inclined conveyor for 35 elevating the excavated soil, of a bucket wheel operably mounted upon the lower end of the conveyor screw and comprising an angle rim, an integral back, buckets extending inwardly from the rim and terminating 40 short of the centre, each bucket being of a scoop-shaped structure for scooping soil and dropping it radially inwardly as it approaches a top position in each revolution 45 of the wheel.

Signed at Mitchell, Ontario, the 12th day of June, 1928.

ROY BURCHILL.
